UNITED STATES PATENT OFFICE

172,970

BOTTLE CARRIER

Charles E. Jones, Chicago, Ill., assignor, by mesne assignments, to American Plasticraft Company, Chicago, Ill., a corporation of Illinois

Application February 5, 1952, Serial No. 18,387

Term of patent 14 years

(Cl. D58—5)

To all whom it may concern:

Be it known that I, Charles E. Jones, a citizen of the United States, residing at Chicago, in the county of Cook and State of Illinois, have invented a new, original, and ornamental Design for a Bottle Carrier, of which the following is a specification, reference being had to the accompanying drawing, forming a part hereof.

In the drawing:

Fig. 1 is a perspective view of a bottle carrier, showing my new design; and

Fig. 2 is a plan view of the carrier.

The designs shown on the exposed end and side of the carrier are repeated on the other end and the other side of the carrier.

The dominant features of the design reside in portions shown in full lines.

I claim:

The ornamental design for a bottle carrier, as shown and described.
